UNITED STATES PATENT OFFICE.

JOHN J. HALLIWELL, OF NEW YORK, N. Y., ASSIGNOR TO R. HOE AND CO., OF NEW YORK, N. Y., A CORPORATION OF NEW YORK.

PRINTING-SURFACE.

1,248,319.

Specification of Letters Patent. Patented Nov. 27, 1917.

Application filed June 14, 1913. Serial No. 773,800.

To all whom it may concern:

Be it known that I, JOHN J. HALLIWELL, a citizen of the United States, residing at New York, county of New York, and State 5 of New York, have invented certain new and useful Improvements in Printing-Surfaces, fully described and represented in the following specification and the accompanying drawings, forming a part of the same.

10 This invention relates to certain improvements in curved printing surfaces of that class in which the plate employed is one page or sheet around the cylinder, this construction having been found to possess cer-

15 tain advantages.

In constructions employed for this purpose, the plates are cast tubular, each being substantially the length of the sheet or page to be printed, as a newspaper page, for instance. This form of plate necessitates a special construction of press for securing the plates in printing position, and, furthermore, such tubular plates require the greatest accuracy in making the plates ready for 20 the press.

It is the object of the present invention to produce a curved printing surface by which these disadvantages of the tubular plate may be avoided and a surface produced which can be applied to a cylinder of ordinary construction and secured thereon by ordinary securing devices, the surface being substantially the size of the sheet or page to be printed. This is accomplished by the 25 present invention by forming the printing surface of two or more curved plates, the meeting edges of which are cast or trimmed to the type line, these plates substantially encircling the cylinder and the total of their 30 printing surfaces producing a single sheet or page. These plates may be produced in any desired manner and may be of any desired number. Preferably, two such plates will be employed for making up the printing surface. These plates may be cast either 35 separately or cast tubular, or substantially tubular. When cast in tubular or substantially tubular form, provision is made for accurately separating the two printing surfaces by casting a narrow strip of plain metal forming a line on which the tubular plate may be divided into two parts, the plates after division being trimmed down to 40 type line. When cast singly, the plates may 45 be cast to the type line or narrow margin

left, which is afterward trimmed off to the type line.

In the accompanying drawing there is illustrated a pair of such printing plates applied to a cylinder. In this drawing— 60

Figure 1 is a view of a pair of plates in printing position removed from the cylinder;

Fig. 2 is a plan view of a portion of four 65 of such plates, showing one means of securing the plates on the cylinder;

Fig. 3 is a detail sectional view showing, on a large scale, the plates in the position they assume on the cylinder, and

Fig. 4 is a diagrammatic end view of a cylinder with a pair of plates fast thereon. 70

In these drawings, 1, 2 indicate the two plates, which are shown trimmed and ready for use. These plates are put on a cylinder 10 of ordinary construction, plate 1, for instance, being applied first and firmly 75 seated against a margin bar 3. Plate 2 is then secured on the cylinder. The abutting edges 4, 5 of the plates are trimmed to the type line and the two plates form a continuous printing surface which is the length 80 of the sheet to be printed. The plates may be secured on the cylinder in any suitable or usual manner. As illustrated, the ends of the plate are beveled and one end takes under a fixed ring 7 on the cylinder and the 85 other beveled edge takes under suitable clamps 8, by which the plates are fastened on the cylinder. The rotation of the cylinder causes the plate 1 to back up against the stop 3 and plate 2 to back up against plate 90 1, so that the meeting edges of the plates are always held tightly together and a continuous printing surface provided.

While the invention has been shown and described as used with a cylinder of ordinary 95 construction and with convenient means for securing such plates on the cylinder, it will be understood that certain changes and variations, both in production of the plates, and in their manner of use, may be made, without departing from the invention. 100

What is claimed is:—

1. In a printing machine, the combination of a plate cylinder and a plurality of curved printing plates thereon disposed around the 105 cylinder, each plate having a printing surface adapted to print part of a page, the edges of said plates being substantially at type-line and abutting to form a continuous printing surface substantially the size of the 110

page to be printed, the abutting edges of the plates extending longitudinally of the cylinder.

2. A printing surface comprising a plurality of curved printing plates, each plate adapted to print part of a page, the edges of said plates being substantially at type-line and abutting to form a continuous printing surface substantially the size of the page to be printed, the abutting edges of the plates extending longitudinally of a support on which the plates are supported.

3. A printing surface formed by dividing a curved printing plate into a plurality of sections, the edges of the sections at the

division point abutting and at such point being substantially at type line, each section of the plate being arranged to print a part of a page and all the sections being arranged to form a continuous printing surface substantially the size of the page to be printed, extending longitudinally of a support on which the sections are supported. 20

In testimony whereof, I have hereunto set my hand, in the presence of two subscribing witnesses. 25

JOHN J. HALLIWELL.
